BUILDING UNIT

Victor J. Hultquist, Alcoa, Tenn.

Application December 15, 1936, Serial No. 116,022

8 Claims. (Cl. 72—30)

This invention is directed to an improvement in building units, preferably of block form, constructed with a view to provide maximum strength and load bearing qualities in use, with particular regard to a construction which will employ the minimum amount of material to avoid undue weight.

The primary object of the invention is the provision of a unit formed with appropriate channels and depressions which in their association with corresponding channels and depressions in adjacent units will afford passages for the reception of reinforcing elements and for the reception of cement grout or filling to form a substantial interlock between adjacent units and to unite all the units of the wall or other structure into a substantially monolithic construction.

A further object of the invention is the provision of a unit in which the channels and depressions are formed vertically, horizontally, and angularly, with respect to the position of the unit to thereby develop maximum resistance to shearing stresses both between the vertical and horizontal contact faces of the component wall units when the assemblage is completed.

A further object of the invention is the provision of the inner or outer face of the unit as a receptor for illuminating means, through the provision of an enlarged recess in the particular face of the unit, together with means for closing the recess with glass or the like to afford direct illumination or with a metal panel which may be covered with a plaster coating to complete the unbroken appearance of the unit.

The invention is illustrated in the accompanying drawings, in which:

Figure 1 is a perspective view showing several units arranged in building relation, each unit being shown as provided with the necessary reinforcement rods, the grout being omitted and each unit being arranged to serve as an illuminating element.

Figure 2 is an end view of one of the units.

Figure 3 is a view, partly in plan and partly in longitudinal section, the line of section being taken below the diagonal channels.

Figure 4 is a vertical section taken on the transverse median line of the unit, the lamp being shown in the housing recess and the transparent plate applied to utilize the unit as an illuminating unit.

Figure 5 is a view in elevation from the inner side of the unit.

Figure 6 is a view in elevation from the inner side of the unit, the lamp and connecting means and the glass plate being omitted.

Figure 7 is an end view, partly in section, of a unit constructed in accordance with the invention, wherein the housing recess is blocked off as when not desired for use as an illuminating unit.

Figure 8 is a view in plan, partly in longitudinal section, showing the arrangement of the modified type of unit wherein the housing recess is utilized merely for dead air space.

It will of course be understood that the building unit of this invention is to be constructed of any appropriate or desired material; can be made in any desired relative dimensions; and that, except in the particulars hereinafter specifically referred to, each unit is a duplicate of every other unit.

The improved unit, which will ordinarily be employed largely as a building block, is here shown as rectangular in shape, though obviously the shape as well as the relative vertical and horizontal dimensions are to be governed by the particular service for which the block is designed. The material employed is such as to permit convenient molding or casting of the unit, particularly with a view to affording substantial and practically identical duplication of all units employed for a particular service.

The block 1 has duplicate upper and lower surfaces 2 and 3 and duplicate end surfaces 4. The outer and inner surfaces of the block 5 and 6 are differently formed as will appear as the description proceeds. The upper and lower surfaces 2 and 3 are each formed with a longitudinally ranging channel 7, semicircular in form and arranged in the mid-width of the unit. Similar side channels 8 and 9 extend in parallelism to the central channel 7, on opposite sides of the central channel and substantially equi-distant from the central channel and the front and rear faces 5 and 6.

The channels 7, 8, and 9 open through the end surfaces of the unit so as to register with similar channels in adjacent blocks on the same level and also register with similar channels in superimposed and underlying units to afford in the assembled units an uninterrupted series of circular channels extending horizontally through the wall or other structure. The channel 7 is connected with the channels 8 and 9 by short transverse channels 10 which serve not only for more effective bonding or interlocking but also have a definite function in connection with reinforcing rods or elements, as will later appear.

A vertical opening 11 extends through the unit from top to bottom centrally of its length and breadth. The end surfaces of the unit, also in duplicate formation, are each provided with a vertically ranging channel 12 arranged at the mid-width of the unit, which channel is of semicircular form in cross section and registers at its upper and lower ends with the respective ends of the channels 7 in the upper and lower faces 2 and 3 of the unit.

Inclined channels 13 and 14, of semicircular form in cross section, lead from open communication with the channels 8 and 9 in each upper

and lower face of the unit to and in open communication with the channel 12. The channels 13 and 14 communicate with the channel 12 in spaced relation longitudinally, that is the channels 13 and 14 leading from the upper surface 2 of the unit leads into the channel 12 materially above the mid-length thereof while the channels 13 and 14 leading from the lower surface 3 of the unit communicate with the channel 12 materially below the mid-length thereof.

The units are assembled in the usual offset building relation wherein an upper unit is arranged above and equally spaced on opposite sides of the line of juncture of two lower units, as clearly shown in Figure 1. The units in any horizontal row are of course in end contact. It is to be particularly noted that the units are laid in assembled or building relation without the use of the usual mortar or cement between them. When assembled in building relation, it will of course be apparent that the channels of each unit will register with similar channels in the meeting surfaces of adjacent blocks to provide circular channels in the assembled units. As a superimposed unit overlies the meeting ends of two underlying units, it is apparent that the hole 11 in the center of each unit is in exact registry with the circular channel formed by the meeting registering channels 12 in the ends of the units supporting the superimposed unit. Therefore, the openings 11 and the meeting channels 12, which latter when in registry form a hole corresponding to opening 11, provide an uninterrupted opening extending vertically through the formation built by the units and that there is obviously such a through opening in the center and at each end of each unit.

The meeting half round channels 12 in the ends of the unit which form a continuation of the central hole 11 of the superimposed unit are open to the channels 8 and 9 on the upper surface 2 of the unit and to the channels 8 and 9 on the lower surface 3 of the unit, through an upper set of inclined channels 13 and 14 which are convergent downwardly and through a lower set of channels 13 and 14 which are divergent downwardly. Of course the channels 8 and 9 and the inclined channels 13 and 14 are, when the units are in assembled relation, circular in cross section by means of the similar registering channels in adjacent units.

Reinforcing elements, such for example as metal rods 16, are passed downwardly through the assembled units through the vertical openings provided by the holes 1 in certain of the blocks formed by the registering channels at the meeting ends of the blocks and the central hole 11 in the underlying and overlying block. Additional reinforcing elements, as rods 16, are passed horizontally through the assembled units, being entered in the openings formed by the registering channels 8 and 9 in the upper and lower surfaces 2 and 3. The vertical ranging reinforced rods may be easily centered in their openings, and to insure an approximate centering of the reinforcing rods 16 in their channels, additional reinforced rods 17 are placed in one or more sets in the transverse channels 10 to underlie and support the reinforcing rods 16, as illustrated in Fig. 1 of the drawings.

Cement grout is then poured into the channels, filling the channels 11 and of course encircling and embedding the reinforcing rods 16, filling the channels 1, 8, and 9, the cross channels 10 and embedding the reinforcing rods 16 and

17, flowing down into the channels 12 and channels 13 and 14, and so being distributed throughout and filling all channels. It is of course to be noted that the cement grout when hardened being an integral rounded element interlocks the blocks one with the other on their upper, lower and end surfaces. These cement grout elements form in effect reinforced keys which interlock the units and provide the function of a truss in each course or layer of the units. The multiple courses are further tied together by the vertical reinforcements as well as their vertical and diagonal grout columns. The result is to form a wall, for example, that can be assembled of simple units in an economical manner and yet when completed will have the strength equivalent to reinforced poured concrete mass of equal thickness.

The diagonal channels 13 and 14 are important for it is apparent that when grout is poured into the registering channels 11 and 12, first tending toward filling horizontal channel 7, then flowing through channels 10, into channels 8, until all the channels are filled, that the air naturally entrained in channels 8 is displaced by the grout and escapes through the lower diagonal channels 13 and 14 into and through channels 12 and 11, which act as vents. Furthermore, the diagonal channels 13 and 14, when filled with grout, provide Y-shaped keys, which offer the greatest resistance to shearing stresses that are set up between the vertical end faces of the wall units. Furthermore, on account of the position of these diagonal keys, there is materially increased resistance as compared with vertical keys against overturning moments acting upon the unit.

An important detail of the present invention is the formation of the units to receive and support lighting elements and to provide for the passage of telephone or other service cables. To provide for this result, one face of the block is formed to provide an enlarged housing recess 18. This recess opens through the inner face of the unit and preferably terminates short of the longitudinal median line, and may have an outline shape corresponding to the shape of the unit, though obviously this may be varied at will. The recesses 18 of adjacent blocks are in communication to horizontally ranging openings 19 leading through the respective end walls of the housing recess, and of course communicating with similar holes of adjacent blocks. Where the housing recess is designed for lighting effect, a lamp 20 is arranged in a socket 21, secured on the bottom of the recess, and conductors 22, 23, are led through the conduits provided by the openings 19. A frame 24 is secured in the mouth of the housing recess and receives and supports, preferably removably, an additional frame 25, carrying a glass plate 26.

While it is contemplated that the formed unit will provide for the reception of illuminating means, it is of course apparent that only certain units will be so used, and it may be that none of the units will be required for this purpose. Where the use of the housing recess is not required for illuminating or other like purposes, an expanded metal panel 27 may be arranged in a recess 28 surrounding the housing recess, and a plaster coating applied to completely close the front of the housing recess, the closure being of course finished to simulate the face of the unit.

The openings 19 form with the housing re-

cesses a continuous channel for the reception of telephone or other cables, as may be necessary, thus affording a convenient means for the running of cables or their replacement even after the units have been assembled in wall or other formation. Of course, if desired, it is contemplated that the housing recess may be formed in both the inner and outer faces of the unit, thus affording lighting from both sides or other treatment involving the use of the recesses. Where the housing recess is only formed in the inner face of the unit, the material of the outer face may be formed with horizontally ranging holes 28' to not only lighten the weight of the unit but to afford convenient dead air spaces for insulating purposes. It will of course be apparent that each housing recess also forms an appreciable dead air space for insulating purposes.

20 The inner and outer marginal edges of each unit is recessed at 29 to provide spaces of appreciable width and depth at the meeting lines of all units to receive mortar or the like, which when appropriately pointed up, acts to seal the joints between the units, preventing the escape of grout or moisture. Furthermore, the mortar applied simulates the appearance of the conventional mortar joints.

It is a well known fact that where external and internal forces act upon a wall, shearing stresses are set up between the horizontal and vertical contact faces of the wall units. It is also well understood that before a wall or structure can fail, there must be some flexure in the wall or its component parts. It is also well understood that shearing stresses precede flexure, therefore in the design of a wall structure made up of a multiple of individual units, where maximum strength in the finished wall is to be developed, resistance to shearing stresses both between the vertical and horizontal contact faces of the component wall units must be introduced. In the present invention, the key or grout channels are so distributed that when the reinforcing elements are introduced in the grout channels, and said channels are filled with cement grout, the grout having hardened and aged, reinforced keys are formed which, due to their form and distribution, offer maximum resistance to shear and flexure.

It will be appreciated that while the openings 18 are above described as particularly designed to receive lighting units, it is, of course, apparent that they may be equally as well employed for the reception of house heating or cooling elements. Any necessary gases or vapors to be used in connection with such elements could obviously be carried in pipes extending through the openings 19.

60 What I claim is:

1. A building unit having the upper and lower faces formed with a longitudinally ranging channel and side channels on opposite sides of the longitudinally ranging channel, the ends of the unit being formed with a vertical channel communicating with the ends of the longitudinally ranging channel, and inclined channels leading from the ends of the side channels and leading into the vertical channel, the inclined channels providing air vent paths from the side channels to the vertical channels.

2. A building unit having the upper and lower faces formed with a central longitudinally ranging channel and with side channels on each side

of and parallel to the central channel, the ends of the unit being each formed with a vertical central channel communicating with the central channels on the upper and lower surfaces, and with inclined channels communicating with the ends of 5 each of the side channels and with the vertical channel, each of the channels being approximately semi-circular in cross section, the inclined channels providing two Y-shaped keys between the ends of adjacent channels and affording en- 10 trained air escape from the side channels to the vertical channels as the side channels are filled with grout.

3. A building unit having the upper and lower surfaces formed with a centrally longitudinal 15 channel, side channels beyond the central channel, a vertical hole at the approximate center of the unit and leading from the central channel of the upper surface to the central channel of the lower surface, the ends of the unit being formed with a vertical channel establishing communication 20 between the central channels on the upper and lower surfaces and with inclined channels establishing communication between the side channels of the upper and lower surfaces and the 25 vertical channel.

4. A construction as defined in claim 2, wherein in the central and side channels of each upper and lower surface of the unit are in communication through transverse channels. 30

5. A wall made up of a series of building units, with the upper and lower surfaces of each unit formed with longitudinally ranging and cross channels registering with opposing surfaces of underlying and superimposed units to provide grout 35 receiving openings, the ends of each unit being formed with vertical and diagonal channels establishing communications with the channels in the surfaces of the unit and registering with corresponding channels in the adjacent horizontal 40 aligned unit to form vertical and diagonal grout receiving openings having free intercommunication with underlying and superimposed units and with adjacent units in horizontal alignment.

6. A construction as defined in claim 5, including the provision of reinforcing elements extending horizontally of the assembled unit in the channels formed in the surfaces of said units and vertically of the assembled units in the channels formed in the ends of such units. 45

7. A construction as defined in claim 5, wherein reinforcing rods are extended through the channels in the upper and lower surfaces of the unit and in the vertical channels at the ends of the unit, with each of the units formed with a substantially centrally arranged vertical opening to 55 register with the cooperating vertical channel in the ends of the units for the passage of the reinforcing rods vertically through the series.

8. A construction as defined in claim 5, wherein reinforcing rods are extended through the channels in the upper and lower surfaces of the unit and in the vertical channels at the ends of the unit, with each of the units formed with a substantially centrally arranged vertical opening to 65 register with the cooperating vertical channel in the ends of the units for the passage of the reinforcing rods vertically through the series, and wherein the cross channels are designed to receive reinforcing rods to underlie and center the reinforcing rods in the longitudinally ranging channels. 70

VICTOR J. HULTQUIST.
